UNITED STATES PATENT OFFICE.

JOHN THOS. FAIRHURST, OF ELIZABETH, NEW JERSEY, ASSIGNOR TO THE J. G. WILSON CORPORATION, OF NEW YORK, N. Y., A CORPORATION OF VIRGINIA.

FOLDING PARTITION.

Application filed April 26, 1924. Serial No. 709,115.

To all whom it may concern:

Be it known that I, JOHN THOS. FAIRHURST, a citizen of the United States, residing at Elizabeth, in the county of Union 5 and State of New Jersey, have invented a certain new and useful Improvement in Folding Partitions, of which the following is a clear, full, and exact description.

This invention relates to folding partitions, and particularly to means for guiding the sections thereof during their turning and their sliding movements.

An object of the invention is to provide means, whereby the top of a section of a 15 folding partition may be guided during its sliding movement, which is relatively steady and frictionless, and which obviates the possibility of binding in cases where the tracks or guides along which the section slides are 20 uneven or imperfectly alined.

Another object is to provide means whereby the section may be guided during its turning or folding movement, so that it will 25 rotate smoothly upon its pivot and will not slide outwardly during its rotation.

Various important features of the invention, together with other objects thereof will appear from the following description taken in connection with the accompanying drawings, in which—

Fig. 1 is a cross-sectional view of a folding partition with the sections thereof unfolded, and shows also in dotted lines the position of the sections when folded;

Fig. 2 is a top view of certain of the sections thereof, illustrating particularly the operation of the guiding means which are operative when the sections are folded;

Fig. 3 is a section on the lines 3—3 in Fig. 2 showing the upper and lower tracks and the various guiding means for a partition section;

Fig. 4 is a sectional view similar to Fig. 3 but showing the guide mechanism of the other section of a pair of partition sections, and also illustrating an alternate type of guide rollers and track therefor;

Fig. 5 is a detail view of the guide rollers and track, shown in Fig. 1; and

Fig. 6 is a detail view of the guiding means operative during the turning movement of the section.

The partition illustrated comprises a plu-

rality of sections 11, 12, 13, 14, 15 and 16. Sections 11, 13 and 15 are respectively joined at one edge to the normally adjacent edge of sections 12, 14 and 16, by hinges 19 which may be of any well-known type. The opposite or normally remote edges of sections 11 through 16 are movably mounted between a track or guideway 20 in the floor and a guideway 22 attached to the upper part of the door casing or to the ceiling. The innermost section 11 is rotatably mounted in any well-known manner, while sections 12 through 16 are rotatably and slidably mounted in the manner now to be described in connection with Fig. 2, which illustrates the mounting and guiding means for section 15, or any section, other than section 11, which is the inward section of a hinged pair.

Section 15, as shown, rides upon rollers 24 which bear upon a bearing surface 25 and may be guided at its base in any well-known manner, such as by a guide member 26 slidably set in a groove 28 in the track or guideway 20. These members should, of course, be of such construction as to permit turning of the sections with respect to the track or guideway 20 in folding. Rotatable and vertically slidable in a bearing 30 in the top of the section and near the edge thereof opposite hinge 19 is a rod 31, on the top of which is a plate 32 on which are mounted four rollers 33. The guideway 22 carries a pair of lateral guide bars 35 and 36 for the rods 31 and has attached to its lower surface a track or guideway 38 for rollers 33. The sides 39 of track 38 are bent inwardly at 40 to form supports for the side faces of rollers 33 to rest thereon. It will be seen that as the sections are turned the rollers will remain stationary in their tracks, and that as the sections are slid along track 20 the rollers will bear against the flanges 40 on track 38 to guide the door in a substantially frictionless manner.

It should be noted that the track 38 carries the weight only of rods 31 and their attachments, the weight of the door being carried by rollers 24. If track 20 is vertically uneven, the door will slide upwardly upon rod 31 without adversely affecting the operation of the rollers. The sides 39 of the track may be made sufficiently far apart and

sufficiently high so that if the track 20 is horizontally uneven the rollers 38 may be slid laterally and the plate 32 may be tipped without interfering with the operation of the rollers.

On a plate 42, which may carry bearing 30, on the top of sections 13 and 15, or any inward section of a hinged pair except the innermost pair, are a stud 44 projecting upwardly toward plate 32 and a segment-shaped lug 45. On the under side of the guide bar 36, on a plane with lug 45, is set a plate 46 having an arcuate edge 47 which cooperates with the arcuate edge of lug 45 to guide the section during its turning movement and to obstruct the outward movement of the section along track 20 during its rotation. Projecting partly over plate 42 is a plate 48, set in guide bar 35, which acts as a stop for stud 44 and provides positive means to prevent an outward movement of the section when in its folded position. These features act to effectively prevent a pair of hinged sections from being unfolded or slid along their track by a person gripping the inward section thereof instead of gripping the outward section, which is the proper mode of opening such a door. This is of importance, because it prevents the strains and stresses likely to be caused on the partition by the unfolding or closing of the sections in an incorrect manner. Arcuate-edged members 45 and 46, moreover, act to guide the section during its rotation, so that it will swing exactly in the correct manner.

Fig. 4 illustrates a variation which may be made in the type of the guides and their track rollers and illustrates this guide mechanism as applied to the outward member of a pair of sections such as a section 18. In this illustration the sides 39' of a track 38' are curved and the edges of rollers 33' are rounded so that the downward and the sideward thrusts of the rollers are carried by a continuous surface of the track.

The term "folding partition" as used herein is intended to signify any door, window, or the like, made up of a plurality of foldable sections, whether used to divide or partially divide a room, or to close or partially close an opening therein.

What I claim as new is:

1. In combination, a rotatable and slideable section of a folding partition, means vertically slideable in the top of said section to guide the same during its sliding movement and to act as a pivot for the same during its rotation, a projection from said section adjacent to said pivot, and stationary means to cooperate with said projection to guide said section and to prevent a sliding movement thereof during its rotation.

2. In combination, a rotatable and slideable section of a folding partition, an upper

track therefor, means to guide the section along said track and to form a pivot for the section during its rotation, a bearing member comprising a lug on said section adjacent to said pivot, a bearing member comprising a stationary plate, a convex edge on one of said bearing members, and a concave edge on the other of said bearing members adapted to cooperate with said convex edge during the rotation of said section to 70 guide the same.

3. In combination, a section of a folding partition, and guiding means therefor comprising a segment-shaped lug on said section and a stationary plate having an annular edge thereon positioned so as to cooperate with said lug during the folding movement of said section.

4. In combination, a slideable and rotatable section of a folding partition, means in 85 the top thereof comprising a plurality of rollers mounted to rotate on substantially vertical axes to guide said section during its sliding movement, and means comprising members having cooperating annular edges 90 to guide said section during its rotation.

5. In combination, a slideable and rotatable section of a folding door, means to guide the section and to prevent it from sliding during its rotation, and vertically adjustable means to guide the section during its sliding movement.

6. In combination, a rotatable and slideable section of a folding partition, a lower track therefor, an upper track shaped like 100 an inverted U and having bent over edges, two symmetrically disposed pairs of rollers adapted to bear against the sides and the bent over edges of said track, and means slidably set in said sections for mounting 105 said rollers.

7. In combination, a rotatable and slideable section of a folding partition, an upper track therefor, means for guiding the section along said track, said means forming 110 a pivot for said section, a bearing member comprising a lug on one side of said pivot, a bearing member comprising a stationary plate, a convex edge on one of said bearing members, a concave edge on the other of 115 said bearing members adapted to cooperate with said convex edge during the rotation of said section to guide the same, a stud on the other side of said pivot from said lug, and a stationary plate serving as a stop for said 120 stud and said section.

8. In combination, a section of a folding partition, vertically slideable guiding means in the top thereof, four rollers mounted to rotate in substantially horizontal planes on 125 said means, and a track for said rollers.

9. In combination, a section of a folding partition, vertically slideable guiding means in the top thereof, four symmetrically disposed rollers mounted to rotate in substan- 130

tially horizontal planes on said means, and a track for said rollers shaped like an inverted **U** and having bent-over edges.

10. In a folding partition comprising a plurality of pairs of hinged sections, gilding means slidably connected to all but the innermost of said sections, four rollers mounted to rotate on substantially vertical axes on said means, a track for said rollers, means on the inward section of an outer pair to guide said section during the folding of said pair, and positive means to prevent said inward section from being moved outwardly when the sections are folded.

15. In combination with the inward section of an outer pair of sections of a folding partition, a lower track, an upper track, four rollers having substantially vertical axes movable in said upper track and mounted on 20 a plate, a rod attached to said plate, a bearing for said rod in the top of said section, said rod being vertically slidable in said bearing and rotatable therein to form a pivot for said section, an arcuate edged lug 25 on said section adjacent to said pivot, a stationary plate having an arcuate edge cooperating with said lug to guide said section during the folding of said pair of sections, and positive means to prevent said pair from 30 being slid outwardly along said tracks when in their folded position.

12. In a sectional partition including sliding and folding sections, anti-frictional guid-

ing means for guiding the sliding movement of the sections, pivotal means for the sections, and means for preventing sliding movement of the sections, during their pivotal movement, said means including corresponding arcuate members adapted for interengagement during pivotal movement of 40 the sections.

13. A folding partition construction comprising a frame, doors mounted for sliding and for pivotal movement in the frame, means for controlling and guiding the doors 45 comprising spindles rotatably mounted in the doors, four rollers mounted on the upper end of each spindle to rotate on axes substantially parallel with the axis of the spindle, and a guideway in said frame with 50 the sides of which said rollers engage.

14. A folding partition construction comprising a frame, doors mounted for sliding and for pivotal movement in the frame, means for controlling and guiding the doors 55 comprising spindles rotatably mounted in the doors, four rollers mounted on the upper end of each spindle to rotate on axes substantially parallel with the axis of the spindle, a guideway in the frame, and oppositely facing channels in said guideway in 60 which the opposite pairs of rollers engage.

Signed at New York, New York, this 24th day of April, 1924.

JOHN THOS. FAIRHURST.
